(21) Appl. No.: **29/181,727**

CLAIM

(22) Filed: **May 16, 2003**

I claim the ornamental design for a cleaning device for
motorcycle disc brake, as shown and described.

(51) LOC (7) Cl. **08-99**

DESCRIPTION

(52) U.S. Cl. **D32/35; D4/120**

FIG. 1 is a perspective view of a cleaning device for
motorcycle disc brake showing my new design;

(58) Field of Search D4/119, 120, 130;
D32/35, 47; 15/104.001, 106, 159.1, 160,
220.3, 220.4; 188/71.1, 71.3, 72.5; 451/63,
254, 261, 262, 290, 393, 486

FIG. 2 is an end elevational view thereof;

(56) **References Cited**

FIG. 3 is an elevational view of the opposing end thereof;

U.S. PATENT DOCUMENTS

FIG. 4 is a side elevational view thereof;

616,593 A * 12/1898 Stanbury, Jr. 15/160
725,843 A * 4/1903 Henn, Jr. 15/160
